CLAIM

The ornamental design for a shoe, as shown and described.

DESCRIPTION

FIG. 1 is a bottom front perspective view of a shoe showing our new design;

FIG. 2 is a bottom view thereof;

FIG. 3 is a bottom rear perspective view thereof;

FIG. 4 is a bottom front perspective view of a shoe showing the design of FIGS. 1-3 in an alternate location on the shoe environment;

FIG. 5 is a bottom view thereof;

FIG. 6 is a bottom rear perspective view thereof;

FIG. 7 is a front perspective view of a shoe showing the design of FIGS. 1-3 in another alternate location on the shoe environment;

FIG. 8 is a side view thereof;

FIG. 9 is a rear perspective view thereof;

FIG. 10 is a bottom front perspective view of a shoe showing an alternate embodiment of our new design;

FIG. 11 is a bottom view thereof;

FIG. 12 is a bottom rear perspective view thereof;

FIG. 13 is a bottom front perspective view of a shoe showing the design of FIGS. 10-12 in an alternate location on the shoe environment;

FIG. 14 is a bottom view thereof;

FIG. 15 is a bottom rear perspective view thereof;

FIG. 16 is a front perspective view of a shoe showing the design of FIGS. 10-12 in another alternate location on the shoe environment;

FIG. 17 is a side view thereof; and,

FIG. 18 is a rear perspective view thereof.

The broken line immediately adjacent to and surrounding the shaded area defines the peripheral bounds of the claimed design and forms no part thereof. The broken lines depicting the remainder of the shoe form no part of the claimed design.

1 Claim, 18 Drawing Sheets
